PLASTIC DOILY

Philip J. Loui, 1001 N. Richmond St., and John J. Motyka, 1841 N. Albany Road, both of Chicago, Ill.

Filed Apr. 28, 1960, Ser. No. 60,352

Term of patent 3½ years

(Cl. D92—26)

Fig. 1 is a top plan view of a plastic doily embodying our new design and showing one-quarter of the design in detail, which design is repeated symmetrically in each of the other three-quarters of the doily.

Fig. 2 is a side elevational view thereof; and

Fig. 3 is an enlarged sectional view taken on the line 3—3 of Fig. 1.

We claim:

The ornamental design for a plastic doily, substantially as shown and described.
